DESIGN FOR A RAIN CAP

Ida R. Cunyus, Beverly Hills, Calif.

Application December 23, 1941, Serial No. 104,809

Term of patent 7 years

To all whom it may concern:

Be it known that I, Ida R. Cunyus, a citizen of the United States of America, residing at Beverly Hills, in the county of Los Angeles, State of California, have invented a new and original and ornamental Design for a Rain Cap, of which the following is a specification, reference being had to the accompanying drawing, forming a part thereof.

Fig. 1 is a side elevational view of a rain cap showing my new design,

Fig. 2 is a rear elevational view of the same,
Fig. 3 is a front elevational view of the same,
and

Fig. 4 is a perspective view of said cap showing the top, front and one side thereof.

I claim:

The ornamental design for a rain cap, as shown.

IDA R. CUNYUS.
